(57) **CLAIM**

The ornamental design for a depth illusion picture frame, as shown and described.

DESCRIPTION

FIG. 1 is a front elevational view of a depth illusion picture frame showing my new design;

FIG. 2 is a left side elevational view thereof;

FIG. 3 is a right side elevational view thereof;

FIG. 4 is a top plan view thereof;

FIG. 5 is a bottom view thereof; and,

FIG. 6 is a perspective view thereof.

The rear of the depth illusion picture frame is flat and unornamented.

A framed picture is shown in dotted lines for illustrative purposes only and forms no part of the claimed design.
